UNITED STATES PATENT OFFICE.

PETER CONOVER, OF FRANKLIN, OHIO.

IMPROVEMENT IN MODE OF ATTACHING SINGLE-TREES.

Specification forming part of Letters Patent No. 42,462, dated April 26, 1864.

To all whom it may concern:

Be it known that I, PETER CONOVER, of Franklin, Warren county, Ohio, have invented a new and Improved Mode of Attaching Single-Trees to their Shaft-Bars; and I do hereby declare the following to be a full, clear, and exact description thereof, reference being had to the accompanying drawings, making part of this specification.

My invention consists in an improved construction of the stay-plates of single-trees, whereby the said stay-plates may be more firmly secured to the single-tree and shaft-bar, respectively, either with or without screws or bolts other than the ordinary king-bolt.

Figure 1 is a perspective view of a single-tree with my improvement. Fig. 2 is a transverse section at the center of the fastening. Fig. 3 is a top view of the stay-plates.

A represents a portion of a shaft-bar. B represents a single-tree secured by customary bolt, C, to the shaft-bar.

D and E are two circular metallic disks, which I call my "stay-plates." One stay-plate, D, is fastened rigidly to the top of the shaft-bar, and the other stay-plate, E, to the bottom of the single-tree in such position that their central apertures, d, receive the same bolt, C, which secures the single-tree, and on which it vibrates. The attachment of the plates is effected in part by wood-screws (see dotted lines F) and in part by lugs G, which project from the plates, so as to inclose the shaft-bar and single-tree, respectively. Segmental flanges H, which project from the stay-plates, serve to limit the vibrations of the single-tree, and

entirely supersede the customary stay-straps.

I am aware that stay-plates of analogous construction to mine have before been applied to shaft-bars and single-trees for the purpose of governing the motion of the latter—as, for instance, in the patent of James Barnes, granted June 11, 1850. This, therefore, I do not broadly claim.

By my invention lugs G, G are provided to support the stay-plates from motion upon their respective bars, so that the ordinary king-bolt, C, will suffice to retain the plates in position, and the plates are prevented from working loose. The wood-screws F are not subjected to strain, being merely depended on to attach the plates to their respective bars when the single-tree is not in position. In this better means of securing the plates to their bars consists the superiority of my invention.

While disclaiming the general idea of providing the opposite faces of the single-tree and shaft-bar with stay-plates to govern the motion of the former, I claim as new and desire to secure by Letters Patent—

The combination of the lugs G, G with the plates D, E, flanges H, H, shaft-bar A, single-tree B, and king-bolt C, when the said parts are all constructed and arranged and operate in the manner and for the purposes herein specified.

In testimony of which invention I hereunto set my hand.

PETER CONOVER.
